(57) **CLAIM**

The ornamental design for a set of keys, as shown and described.

DESCRIPTION

FIG. 1 is a perspective front view of a set of keys showing our new design;

FIG. 2 is a front view thereof;

FIG. 3 is an enlarged perspective front view of a left key from FIG. 1, shown in isolation;

FIG. 4 is an enlarged perspective front view of a right key from FIG. 1, shown in isolation;

FIG. 5 is an enlarged cross-diagonal side view of the key from FIG. 3; and,

FIG. 6 is an enlarged cross-diagonal side view of the key from FIG. 4.

The broken line adjacent the shaded region of the set of keys represents an unclaimed boundary of the design and the broken line showing of the remainder of the handset and the individual keys is directed to environment and is for illustrative purposes only; the broken lines form no part of the claimed design.
